ENGINE

Andre J. Meyer, Detroit, Mich., assignor to Continental Motors Corporation, Detroit, Mich., a corporation of Virginia

Application April 30, 1932, Serial No. 608,366

14 Claims. (Cl. 123—81)

This invention relates to internal combustion engines and refers more particularly to sleeve valve engines although certain of my improvements described herein are not necessarily limited to engines of the sleeve valve type.

It is an object of my invention to provide an improved sleeve valve driving mechanism especially adapted for operating associated pairs of sleeve valves such as the companion sleeves of associated cylinders in a V-type engine. Because of the relative angle of such companion sleeves, many problems arise in regard to driving the sleeves, especially where a single layshaft is employed. I have overcome these problems by providing, in the illustrated embodiment of my invention, a single layshaft adapted to operate a cross-shaft for companion sleeves, the cross-shaft having hinged or pivoted crank arms for actuating the respective sleeves. This phase of my invention is particularly adapted for actuating single sleeve valves of the combined movement type wherein the single sleeve per associated engine cylinder is given a combined oscillating and reciprocating movement in performing the customary engine valving functions. My invention is not limited, however, to sleeve valve engines of any particular type or movement or any particular number of sleeve valves for each cylinder.

A further object of my invention resides in the provision of means for actuating the sleeve valve at a point above the inner end of the cylinder, such actuation providing less sleeve distortion and thrust than when the sleeve is actuated from its end as is now customary. In order to conveniently assemble the sleeve and provide good bearing for the sleeve, I have provided a removable cylinder part, preferably bounding the inner part of a cylinder opening through which the sleeve drive extends for attachment to the sleeve. Such arrangement also provides an improved arrangement of layshaft between the V formed by the cylinders and makes for a very light weight, low cost, engine having its valve parts readily accessible for inspection.

A further object of my invention resides in the provision of an improved sub-assembly of the valve actuating mechanism and an improved housing for the layshaft between cooperating half portions of the V-cylinder block.

Further objects and advantages of my invention will be apparent as this specification progresses, reference being had to the accompanying drawing in which:

Fig. 1 is a sectional elevation view transverse-

ly of the engine through a pair of companion V-cylinders.

Fig. 2 is an enlarged view of the sleeve valve driving means as shown in Fig. 1.

Fig. 3 is a view similar to Fig. 2 but showing the sleeve cranks advanced through 180° from their Fig. 2 position.

Fig. 4 is a sectional view longitudinally through the central part of the engine, along the line 4—4 of Fig. 1.

Fig. 5 is a detail side view of a portion of a typical cylinder showing the cylinder wall opening receiving the sleeve driving lug, and

Fig. 6 is a sectional elevation view through the detachable cylinder wall portion, as along the line 6—6 of Fig. 5.

In the drawing, the engine A has rows or banks of cylinders in V-formation although many of the features of my invention are not necessarily limited to any particular arrangement of cylinders. A pair of companion cylinders 10 and 11 are shown in Fig. 1, the description being limited to one cylinder hereinafter as all of the engine cylinders are similarly constructed and have similar parts associated therewith. Cylinder 10, for example, has the usual intake and exhaust ports 12 and 13 respectively, the intake and exhaust manifolds being represented at 14 and 15 respectively. Within the cylinder is located the sleeve valve means, herein shown as a single sleeve valve 16 of the aforesaid combined movement type whereby any point on the sleeve traces a closed curve path with respect to the cylinder wall, the curve being usually in the general form of an ellipse or circle. Within sleeve 16 is a piston 17 actuating connecting rod 18 for rotating crank-shaft 19 in the customary manner, the connecting rods 18 of cylinders 10 and 11 being articulated if desired (not shown but customary and well understood).

The two cylinder rows respectively are aligned with cylinders 10 and 11 and are separately cast to form companion cylinder block sections B and C joined vertically at 20, then around the crank-shaft bearings at 21 and terminating horizontally at 22. A bearing housing cap 23 forms the crankcase cover or oil pan and takes the downward thrust from crankshaft bearing portion 24, the latter having a companion bearing portion 25, these parts forming the engine crankcase inwardly of cylinders 10 and 11. The cap 23 is secured to block sections B and C by bolts 26 and the block sections B and C are tied together by bolts or fastening assemblies 27 and 28. The crankshaft bearing, bolt assemblies, and asso-

ciated parts are claimed in my co-pending application Ser. No. 608,367, filed April 30, 1932.

Cylinder 10 has an opening 29 through the wall thereof above the crankcase and toward the 5 sleeve driving mechanism D, the opening being sufficient to accommodate movement of the sleeve driving lug 30 which extends outwardly through the opening perpendicularly with the sleeve axis, the lug having a ball portion 31. The 10 opening 29 is bounded inwardly of the cylinder above the crankcase by a detachable cylinder element 32 preferably forming a continuation of the arcuate inner cylinder end formed by the main portion of the cylinder block B as shown in Figs. 15 1 and 6. The cylinder element 32 is secured in place by studs 33 and is attached after assembling the sleeve through the crankcase outwardly of the cylinder. With cylinder element 32 removed, the opening 29 provides a slot in the cylinder 20 wall opening to the crankcase to receive the lug 30 during assembly of the sleeve.

The driving mechanism D comprises a layshaft 34 having spaced bearings 35 and intermediate gears 36, the latter actuating gears 37 to rotate 25 the cross-shafts 38 supported in bearings 39. At each end of each cross-shaft is a crank 40 pivoted thereto by pin 41 and formed with socket 42 having the cap 43 secured in place by fasteners 44. The cross-shafts 38 have their axes horizontal 30 or at an angle out of perpendicular with the sleeve axes so that as cranks 40 are rotated they will swing on pivots 41 and move around ball portions 31 to impart the aforesaid movement to the sleeve valves.

35 The driving mechanism is built up as a sub-assembly and clamped in position between the cylinder block sections B and C. Thus, I have provided a frame formed in complementary halves 45, each having openings 46 for gears 37 and semi-cylindrical openings 47 for receiving layshaft bearings 35. The companion side walls 48 form lubricant pockets and the frame halves 45 are fastened together prior to installation in the engine by reason of connecting fasteners 49 to each side of gears 37 and by fasteners 50 at the openings 47. The block sections B and C have complementary openings 51 for receiving the spaced cylindrical portions 52, these portions having the aforesaid openings 47. The sub-50 assembly including frame parts 45, layshaft 34, gears 36 and 37, and cranks 40, is placed in position between the block sections B and C. The sleeve ball 31 is then placed in socket 42 and cap 43 is then secured in place to couple the crank and sleeve valve for driving.

Referring to Fig. 4, I have illustrated a driving gear arrangement for the valve shaft, the particular embodiment being adapted especially for use as an aircraft engine, either arranged as 60 shown or inverted. Thus the crankshaft gear 53 drives gear 54 carrying propeller shaft 55 and on this shaft is a pinion 56 driving layshaft 34 by reason of the layshaft gear 57. For a fourstroke cycle engine the layshaft is driven at half crank-65 shaft speed as usual, and the propeller shaft 55 is also driven at a reduced speed from the crank-shaft.

While I have shown and described one embodiment of my invention in detail it is not my intention to limit my invention to such detail parts since various changes and modifications will be readily apparent from the teachings of my invention.

What I claim as my invention is:

75 1. In an engine of the sleeve valve type, a pair of

V-arranged cylinders, a sleeve valve associated with each cylinder, a layshaft intermediate said cylinders and having a driving gear, a cross-shaft having a gear driven by said driving gear and extending at an angle out of perpendicular with each sleeve axis, and means for operating said sleeves from said cross-shaft.

2. In an engine of the sleeve valve type, a pair of V-arranged cylinders, a sleeve valve associated with each cylinder, a layshaft intermediate said cylinders and having a driving gear, a cross-shaft having a gear driven by said driving gear and extending at an angle out of perpendicular with each sleeve axis, and means for operating said sleeve from said cross-shaft, with a combined 15 reciprocating and oscillating motion.

3. In an engine of the sleeve valve type, a pair of V-arranged cylinders, a sleeve valve associated with each cylinder, a layshaft intermediate said cylinders and having a driving gear, a cross-shaft 20 having a gear driven by said driving gear and extending at an angle out of perpendicular with each sleeve axis, a driving lug projecting laterally from each sleeve, and a crank pivoted to said cross-shaft at each end thereof and connected to 25 drive one of said lugs.

4. In an engine of the sleeve valve type, a pair of V-arranged cylinders, a sleeve valve associated with each cylinder, a layshaft intermediate said 30 cylinders and having a driving gear, a cross-shaft having a gear driven by said driving gear and extending at an angle out of perpendicular with each sleeve axis, a driving lug projecting laterally from each sleeve, and a crank pivoted to 35 said cross-shaft at each end thereof and universally connected to one of said lugs whereby to permit each crank to swing on its pivot to move its associated sleeve with combined reciprocation and oscillation.

5. In an internal combustion engine having a 40 pair of V-cylinders, sleeve valve means associated with each of said cylinders, a layshaft between said cylinders, and means intermediate the lay-shaft and sleeve valve means for driving the sleeve valve means from said layshaft, said lay-shaft being common to both cylinders, said sleeve driving means including crank members driven by said common layshaft, the axes of said crank members extending substantially perpendicular to the axis of the layshaft.

6. In an internal combustion engine having a pair of V-cylinders, sleeve valve means associated with each of said cylinders, a layshaft between said cylinders, and means for driving the sleeve valve means from said layshaft, said driving 55 means including a swinging crank for each of said sleeve valve means whereby to impart combined oscillation and reciprocation to said sleeve valve means.

7. In a V-type engine, companion cylinder 60 block sections forming the longitudinally extending pairs of cylinder rows, sleeve valve means associated with the cylinders, said sections having face contact vertically between the cylinder rows and formed with longitudinally spaced cooperating pair of recesses, and a single layshaft common to said cylinder rows and extending longitudinally of the engine between the cylinder rows, said layshaft having spaced bearings within said recesses, and sleeve driving means between 65 said layshaft and sleeve valve means, said sleeve driving means including crank members driven by said common layshaft, said crank members having axes extending substantially perpendicular to the layshaft axis.

8. In a V-type engine, companion cylinder block sections forming the longitudinally extending pairs of cylinder rows, sleeve valve means associated with the cylinders, said sections having face contact vertically between the cylinder rows and formed with longitudinally spaced cooperating pair of recesses, and a layshaft extending longitudinally of the engine between the cylinder rows, a frame structure journaling said layshaft, longitudinally spaced cross-shafts journaled in said frame structure and geared with said layshaft for driving the sleeve valve means, said frame structure having longitudinally spaced cylindrical portions clamped between said pairs of recesses respectively.

9. In an engine having a pair of cylinder rows, sleeve valve means associated with the cylinders, a layshaft, a mechanism driven by the layshaft and adapted to drive said sleeve valve means, a frame structure carrying said layshaft and sleeve driving mechanism and providing a unit sub-assembly thereof, and means for securing said sub-assembly in position between said cylinder rows.

10. In an engine of the sleeve valve type, a crankcase, a pair of V-arranged cylinders extending outwardly from the crankcase and having adjacent side walls each provided with an opening, said openings being spaced outwardly of the cylinder from said crankcase, sleeve valve means associated with and moving axially within each of said cylinders, and means outwardly of the crankcase and including a common layshaft and sleeve actuating devices operated by said layshaft and extending in substantially opposite directions into said openings for operating the sleeve valve means, the inner end portions of said sleeve valve means operating in zones inwardly of the openings.

11. In an engine of the sleeve valve type, a crank case, a pair of V-arranged cylinders extending outwardly from the crank-case and having adjacent side walls each provided with an opening, said openings being spaced outwardly of the cylinder from said crankcase, sleeve valve means associated with and having a movement axially within each of said cylinders and means outwardly of the crankcase extending into said openings for operating the sleeve valve means, the inner end portions of said sleeve valve means operating in zones inwardly of the openings, said sleeve valve operating means including oppositely extending sleeve actuating elements and a common layshaft driving said actuating elements and operating in the zone intermediate said V-arranged cylinders and operating in the zone intermediate said V-arranged cylinders.

12. In an engine of the sleeve valve type, a crankcase, a pair of V-arranged cylinders extending outwardly from the crankcase and having adjacent side walls each provided with an opening, said openings being spaced outwardly of the cylinder from said crankcase, sleeve valve means associated with and having a movement axially within each of said cylinders and means

13. In an engine of the sleeve valve type, a crankcase, a pair of V-arranged cylinders extending outwardly from the crankcase and having adjacent side walls each provided with an opening, said openings being spaced outwardly of the cylinder from said crankcase, sleeve valve means associated with and having a movement axially within each of said cylinders and means outwardly of the crankcase extending into said openings for operating the sleeve valve means, the inner end portions of said sleeve valve means operating in zones inwardly of the openings, said sleeve valve operating means including oppositely extending sleeve actuating elements and a common layshaft driving said actuating elements and operating in the zone intermediate said V-arranged cylinders, said sleeve valve means each having sleeve driving members operatively connected with said elements and received in said openings during assembly of the sleeve valve means within said cylinders.

14. In an engine of the sleeve valve type, a crankcase, a pair of V-arranged cylinders extending outwardly from the crankcase and having adjacent side walls each provided with an opening, said openings being spaced outwardly of the cylinder from said crankcase, sleeve valve means associated with and having a movement axially within each of said cylinders and means outwardly of the crankcase extending into said openings for operating the sleeve valve means, the inner end portions of said sleeve valve means operating in zones inwardly of the openings, said sleeve valve operating means including oppositely extending sleeve actuating elements and a common layshaft driving said actuating elements and operating in the zone intermediate said V-arranged cylinders, said sleeve valve means each having sleeve driving members operatively connected with said elements and received in said openings during assembly of the sleeve valve means within said cylinders, said cylinder structure having inner portions surrounding the sleeve valve means in each of said V-arranged cylinders inwardly of said openings, said cylinder inner portions each having an arcuate bearing surface engaged by said sleeve valve means.
